United States Patent

Des. 237,700
Patented Nov. 18, 1975

237,700

PORTABLE DISPLAY CART

Richard Allen Clarke, Greenwich, and William James Chvala and Raymond Edward De Witte, Danbury, Conn., assignors to PepsiCo, Inc., Purchase, N.Y.

Filed Aug. 8, 1974, Ser. No. 495,918

Term of patent 14 years

Int. Cl. D12—02

U.S. Cl. D12—30

FIG. 5

FIG. 4

FIG. 3

FIG. 1 is a right front perspective view of a display cart showing our new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a right front perspective view thereof with the lower extension shelf omitted showing an alternate arrangement; and

FIG. 8 is a right front perspective view thereof with the upper shelf and back extension omitted showing an alternate arrangement.

The bottom of the display cart is substantially flat and unornamented.

We claim:

The ornamental design for a portable display cart, as shown and described.
